UNITED STATES PATENT OFFICE.

FREDERICK J. WALLACE, OF BUFFALO, NEW YORK.

DESIGN FOR A BROOM-HOLDER.

SPECIFICATION forming part of Design No. 32,388, dated March 27, 1900.

Application filed January 29, 1900. Serial No. 3,236. Term of patent 31 years.

To all whom it may concern:

Be it known that I, FREDERICK J. WALLACE, a citizen of the United States, residing at Buffalo, in the county of Erie and State of New York, have invented and produced a new and original Design for a Broom-Holder, of which the following is a specification.

This invention relates to a new and useful design for a broom-holder; and the essential feature resides in a rectangular supporting-plate having arms of compound-curved form extending from the opposite side edges and in planes at a right angle to the said support.

In the drawings, Figure 1 is a perspective view of a broom-holder embodying the features of the design. Fig. 2 is a horizontal section of the holder.

The numeral 1 designates a rectangular support which is elongated and has circular openings 2 therein near opposite ends. The support 1 is flat, and extending from intermediate

points of the side edges are arms 3, which have flat portions 4 adjacent the support, continuing into convex seats 5, and from the outer portions of the said seats reversely-curved lips 6 project. The arms 3 extend away from the support 1 in planes at right angles to the latter and are of equal length. The arms also present unbroken surfaces and are of continuous construction in a transverse direction.

Having thus described the invention, what is claimed as new is—

The design for a broom-holder, herein shown and described.

In testimony that I claim the foregoing as my own I have hereto affixed my signature in the presence of two witnesses.

FREDERICK J. WALLACE.
